The ornamental design for a kit for a Christmas tree surround, as shown and described.

DESCRIPTION

FIG. 1 is a an environmental perspective view of a kit for a Christmas tree surround showing my new design;

FIG. 2 is an enlarged front elevational view of the fence panel, gate and fence post, shown separately for clarity of illustration;

FIG. 3 is a rear elevational view of FIG. 2;

FIG. 4 is a top plan view of FIG. 2; and,

FIG. 5 is a right side elevational view of FIG. 2, the left side being a mirror image.

The bottom of the present design is plain and unornamented. The broken line showing of a Christmas tree within the design and lights atop the connecting post components of the design are for illustrative purposes only and form no part of the present design.
